UNITED STATES PATENT OFFICE.

HOWARD B. SHERMAN, OF BATTLE CREEK, MICHIGAN.

CLEAT.

1,163,269.

Specification of Letters Patent.

Patented Dec. 7, 1915.

Application filed April 2, 1915. Serial No. 18,709.

To all whom it may concern:

Be it known that I, HOWARD B. SHERMAN, a citizen of the United States, residing at Battle Creek, in the county of Calhoun and State of Michigan, have invented certain new and useful Improvements in Cleats; and I hereby declare that the following is a full, clear, and exact description thereof, reference being had to the accompanying drawings, which form part of this specification.

This invention is a novel cleat especially designed for use in securing in position sheets or strips of paper, felt or composite material such as are commonly used for sheathing and roofing buildings and the like; and its object is to provide cleats which can be readily applied where desired and can be either spaced apart, as desired, or may be placed in line close together to form a practically continuous bond; and which cleats will not only bind the lapped portions of the sheets securely together and in place but will also protect the edges of the outermost lapped sheets or strips.

The invention consists in a novel cleat, preferably stamped from sheet metal, and which is light but so stiffened by peculiar ribs and bends that it is substantially rigid and will securely bind the lapped portion of the sheets and exclude moisture from beneath such cleat.

I will explain the invention with reference to the accompanying drawings in which:

Figure 1 is a perspective view of one of the cleats applied to the lapped portion of two sheets of material. Fig. 2 is a bottom view of the cleat detached and about full size. Fig. 3 is an enlarged transverse section of the cleat on the line 3—3, Fig. 2. Fig. 4 is a further enlarged view showing how the ends of two adjacent cleats may be constructed to lap when the cleats are to be placed close together to form a practically continuous bond. Fig. 5 is a detail section on the line 5—5, Fig. 4.

The cleat is preferably stamped out of sheet metal and may be made of any desired length, being preferably about five inches long. The main body 1 of the cleat is flat, but it is provided along one side with a longitudinal L-shaped flange the vertical portion 2 of which flange is adapted to abut against the edge of the outer sheet of material S upon which the cleat is

placed, while the lower portion 3 of this L-shaped flange is adapted to rest upon the under sheet of material S². The part 2 of the flange affords a ready means for positioning the cleat accurately over the lapped portions of the sheets and against the edge of the outer lapped sheet and greatly facilitates the application of the cleat. Such flange also protects the edge of the sheet from the elements and thereby greatly enhances the durability of the exposed edges of such sheet. The main body 1 of the cleat is also provided with an integral longitudinal rib 4 which may be stamped from the metal of the body and preferably extends adjacent the edge of the body remote from the flange 2. Said rib is preferably concavo-convex in cross section and considerably wider than it is high; the top part 75 of this rib being approximately flat and broad enough to afford a good bearing for the heads of the nails N by which the cleat is secured in position. The ends of rib 4 are deflected at right angles to the main 80 part thereof as shown at 5, said end portions 5 extending across the body 1 and down part 2 of the flange and merging into the part 3 of the flange as indicated in the drawings. The rib 4 and flange 2—3 stiffen 85 the cleat longitudinally; and the end portions 5 of the rib stiffen the cleat transversely. By reason of these transverse end portions 5 of the rib the base parts 3 of the flange 2—3 are firmly pressed down when the 90 cleat is secured by the fastening nails N. The said cleats may be spaced apart if desired or they may be placed close together end to end and lapped as indicated in Fig. 4 to form a continuous fastening means 95 along the edges of the sheets S, S². When the cleats are to be lapped one end of each cleat may be slightly shouldered as at 6 to overlap the end 7 of the adjacent cleat, as indicated in Figs. 4 and 5. These cleats 100 can be readily positioned by laying them upon the outer lapped sheet and alining them thereon by bringing their flanges 2 against the edge S of such sheet, and thus no time is lost in properly and similarly locating the cleat in alinement upon the edge of the sheet. Such cleats not only bind the upper layer S, but also bind the lower layer S² and also protect the edge of the sheet S as stated.

What I claim is:

1. A cleat comprising a metal body hav-

ing a longitudinal down-turned flange on one side and a raised longitudinal rib at its opposite side parallel with said flange, said rib having end portions extending transversely of the strip.

2. A cleat for the purpose specified comprising a metal strip having a down-turned flange on one edge and a longitudinally disposed rib adjacent its other edge, said rib 10 having end portions extended across the strip and down the vertical portion of the flange.

3. A cleat for the purpose specified comprising a metal strip having an L-shaped 15 flange on one edge and a longitudinally disposed rib adjacent its other edge, said rib having its end portions extended transversely of the strip and down the vertical portion of the flange to the base portion 20 thereof, the rib being perforated for the passage of nails.

4. A cleat for the purpose specified comprising a metal strip having an L-shaped flange on one edge and a longitudinally disposed rib adjacent its other edge, said rib 25 being concavo-convex in cross section and

formed integral with the strip by stamping it out of the body thereof, and said rib having its end portions extended transversely across the strip and down the vertical portion of the flange to the base portion thereof. 30

5. The herein described cleat comprising a sheet metal strip having an L-shaped flange on one edge and a longitudinally disposed rib adjacent its other edge, said rib 35 having its end portions extended angularly across the strip and down the vertical portion of the flange into the base portion thereof, said rib being flat and concavo-convex in cross section and having a broad top surface, said rib being formed integral with the strip by stamping it out of the body of the strip; the rib being also perforated for the passage of nails. 40

In testimony that I claim the foregoing 45 as my own, I affix my signature in presence of two witnesses.

HOWARD B. SHERMAN.
